Attorney

UNITED STATES PATENT OFFICE.

WILLARD R. KOEN, OF FLAT RIVER, MISSOURI.

ELECTRIC CARTRIDGE-FUSE.

1,190,773.

Specification of Letters Patent. Patented July 11, 1916.

Application filed February 24, 1915. Serial No. 10,289.

To all whom it may concern:

Be it known that I, WILLARD R. KOEN, a citizen of the United States, residing at Flat River, in the county of St. Francois, State of Missouri, have invented certain new and useful Improvements in Electric Cartridge-Fuses; and I do hereby declare the following to be a full, clear, and exact description of the invention, such as will enable others skilled in the art to which it appertains to make and use the same.

This invention relates to new and useful improvements in electric cartridge fuses.

An object of the invention resides in constructing the fuse in such manner that the fusible strip is detachably secured within the barrel or shell so that after having been broken by an overload on the circuit in which it is interpolated it may be removed and replaced by a new strip.

A further object of the invention resides in so constructing the device that the removal of the old or fused strip and the replacing of it by a new strip may be accomplished speedily and with very little trouble.

A further object of the invention resides in so constructing the device that the strip will be effectively clamped in place on the blades.

A still further object resides in the provision of common means for producing the clamping action on the ends of the fusible strip and for attaching the caps to the barrel.

With these and other objects in view, such as will appear as the description progresses, my invention comprises the combination and arrangement of parts as set forth in and falling within the scope of the appended claims.

Referring to the drawing: Figure 1 is a longitudinal sectional view of a fuse constructed in accordance with my invention, looking at the clamping side of the blades showing the same and the fusible strip in elevation. Fig. 2 is a perspective view of the blades and the fusible strip with the caps and the barrel removed. Fig. 3 is a section on line 3—3 of Fig. 1, showing the relation of the blades, the fusible strip and the wedge blocks. Fig. 4 is a sectional view taken longitudinally of one of the blades, showing the coöperation of the adjacent block and the blade to clamp the fusible strip.

Referring to the drawing wherein like

parts are indicated by like characters throughout the several views: The barrel 1 is composed of fiber or any other suitable insulating material and is provided with end caps 2. In order that a fusible strip may be maintained in this barrel 1, I have provided blades 3 which extend through slots 4 in the ends of the caps 2 and are prevented from outward movement beyond a predetermined point by shoulders 5 on the said blades. These blades are made of a strip of heavy metal such as copper or the like. This strip is bent back upon itself, as indicated in the drawing, and secured together by rivets 6. The inner end of each of these blades is provided with oppositely extending lugs 7 which extend into slots 8 in the barrel 1 and prevent the rotation of the blade and adjacent cap with relation to the barrel.

In order that the fusible strip 8' which extends from one blade to the other may be secured to the blades, I have constructed the inner end of each of the blades with spaced arms 9 which extend outwardly from the plane of the blade. These arms are constructed with inclined portions 10 and perpendicular end portions 11 and a slot 12 is provided between the said arms, the purpose of which will later appear. The perpendicular portions 11 have cut-out portions 13.

Detachably mounted on the end of each of the blades 3 is a clamping block 14 which has a body portion 15 adapted to extend upwardly through the space 12 between the arms 9 and wedge-shaped flanges 16 adapted to pass through the cut-out portions 13 and ride beneath the arms 9. The upper or cam faces 17 of the flanges 16 are adapted to bear against the lower faces 18 of the inclined portions of the arms 11 so that as the clamping block is drawn inwardly into the space 12 between the arms 9 a clamping action will be produced between the said block and the base of the blade 3. Now when the end of the fusible strip 8' is interposed between the said base and the clamping block upon the inward movement of the clamping block it will be clamped in position and effectively secured to the blade. In order that this clamping action may be effective, I have provided the body portion 15 of each block 14 with a threaded hole and the adjacent cap 2 with a hole through which a screw 19 passes, the tightening of which screw will cause the block 15 to clamp the adjacent end

of the fusible strip and maintain the blade, barrel and cap in rigid relationship.

From the foregoing description it will be seen that I have provided a cartridge fuse 5 in which the fusible strip may be speedily removed and replaced by a new strip.

It will be further seen that I have so constructed the device that the fusible strip will be frictionally clamped on the blades. I 10 have further so constructed the blades, the clamping block and the caps that but a single screw is necessary to clamp one end of the fusible strip and the adjacent blade and cap.

15 I have further constructed the device so that fusible strips of various thicknesses may be maintained in position therein.

While I have illustrated and described a particular embodiment of my invention I 20 have merely done so for the sake of convenience and I do not wish to be limited to that particular embodiment as it is obvious that numerous changes may be made within the details of construction thereof without in 25 any way departing from the spirit of the invention or exceeding the scope of the appended claims.

What I claim is:—

1. In a cartridge fuse, the combination 30 with an insulating barrel having slots in one end thereof, of a cap mounted on said end, a blade extending through said cap and having lugs extending into said slots, a

clamping block slidably mounted on said blade, a fusible strip having one end disposed between the sliding block and blade and having its other end secured to the opposite end of the barrel, the said blade having cam faces thereon coöperating with said clamping block to force the same into engagement with the strip and a screw in threaded engagement with the clamping block and extending through the cap to effect the clamping action between the said block and base to maintain the cap upon the end of the barrel.

2. In a cartridge fuse, the combination with a blade having spaced arms extending outwardly from one end of the base thereof, the said arms being provided with inclined portions and portions perpendicular to the base, and a clamping block having a body portion extending between the said arms and wedge-shaped portions arranged to ride beneath the inclined portions of the arms whereby a fusible strip may be clamped between the said clamping block and the base upon the inward movement of the clamping block.

In testimony whereof, I affix my signature, in the presence of two witnesses.

WILLARD R. KOEN.
